(57) **CLAIM**

The ornamental design for a straw cap, as shown and described.

DESCRIPTION

FIG. 1 is a front, top perspective view of a straw cap, showing my new design;

FIG. 2 is a rear, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a sectional view of 9-9 along the line in FIG. 3; and, FIG. 10 is a front, top perspective view of the straw cap, indicating the usage environment.

The dashed broken lines in the figures are for the purposes of illustrating portions of the straw cap that form no part of the claimed design.

The dashed broken lines in the FIG. 10 are for the purposes of indicating the usage environment of the straw cap and form no part of the claimed design.

1 Claim, 10 Drawing Sheets
